Primary Examiner—Susan J. Lucas*Attorney, Agent, or Firm*—Fulwider, Patton, Lee & Utecht[57] **CLAIM**

The ornamental design for a fluorescent light fixture, as shown and described.

DESCRIPTION

FIG. 1 is a top, front perspective view of a fluorescent light fixture showing my new design;

FIG. 2 is a fragmentary front elevational view thereof on an enlarged scale;

FIG. 3 is a fragmentary top plan view thereof on an enlarged scale;

FIG. 4 is a bottom plan view thereof on an enlarged scale;

FIG. 5 is a left hand end elevational view thereof on an enlarged scale; and,

FIG. 6 is a right hand end elevational view thereof on an enlarged scale.

The light in FIGS. 2, 3, 4, and 5 is broken away for convenience of illustration.

FIG. 1

FIG. 2

FIG. 3

FIG. 4

FIG. 6

FIG. 5
